SAFETY BOXCAR DOOR

William Joseph Lewis, Lexington, Ky.

Application October 6, 1938, Serial No. 233,682

1 Claim. (Cl. 20—30)

This invention relates to freight-cars and more particularly to the doors of that type of freight-cars known as boxcars.

The primary object of this invention resides in the provision of a freight-car door adapted to safeguard the contents of the freight-car against loss by pillage, where valuable freight is being transported.

Another object of this invention resides in the provision of a freight-car door of such construction it cannot be opened without a special tool.

A further object of this invention resides in the provision of a freight-car door consisting of a plurality of sections adapted to be locked against removal upon locking a certain section thereof.

A still further object of this invention resides in the provision of a freight-car door consisting of companion sections adapted to be movably connected to the body of the freight-car so as to prevent loss thereof when removed from their closed position.

Aside from the aforesaid objects, this invention resides in a freight-car door consisting of a plurality of companion sections adapted to be retained in closed relation by certain interlocking means.

Among the many objects of this invention is the provision of particularly constructed locking means for the door.

With these and other objects in view this invention resides in certain novel features of construction and arrangement of elements to be hereinafter more fully set forth in the specification, illustrated in the accompanying drawings and pointed out in the appended claim and, while this disclosure depicts my present conception of the invention, the right is reserved to resort to such changes in construction and arrangement of parts as come within the scope of the appended claim.

In the accompanying drawings forming a part of this application

Fig. 1 is a side view of a portion of a freight-car showing the door in closed position, thereon.

Fig. 2 is a cross sectional view thereof approximately on line 2—2 of Fig. 1.

Fig. 3 is a longitudinal sectional view thereof approximately on line 3—3 of Fig. 2.

Fig. 4 is a detail sectional view approximately on line 4—4 of Fig. 1 showing one of the locking bolts.

Fig. 5 is a detail perspective view of two of the door sections disposed in juxtaposition.

Fig. 6 is a detail sectional view approximately

on line 6—6 of Fig. 4 showing one of the bolt-receiving lugs.

Fig. 7 is a detail perspective view of a portion of one of the guide-rails.

In the present illustration of this invention, the letter A designates a portion of the conventional box type freight car which among other adjacents thereof is provided with a doorway B having a door 5. Suitably secured to each opposite vertical edge of the doorway is a guide-rail 6 which preferably consists of a piece of metal having a portion thereof offset as at 4 and provided with open notches 8 disposed in its edge for a purpose to be hereinafter set forth.

The door 5 consists of a plurality of horizontally disposed sections 9 provided with pairs of vertically spaced round lugs 10 on their opposite ends, each section, other than the bottom and top sections 9' and 9'' are also provided at its upper edge with lugs 11 having elongated apertures 12 therein to accommodate tongues 13 formed on or otherwise secured to the lower edges thereof so as to lock the sections together against bulging.

The bottom section is provided with apertured lugs 11' at its upper edge to receive the tongues on the section above and also with elongated lugs 14 at its lower edge for seating in apertures 15 formed in the sill or bottom of the doorway.

Secured to each section 9 is a flexible element 30 preferably in the form of a chain 17 having its opposite ends secured to a substantially U-shaped bracket 18 suitably attached to the top of the freight-car adjacent the doorway, said chains being of such lengths as will permit the sections 35 to be removed from the doorway and allowed to hang against the side of the freight-car.

The top section is provided at its lower edge with tongues 13' adapted to be seated in the apertures of the lugs 11 on the section below 40 and is adapted to be secured against unauthorized removal by bolts 19 disposed adjacent its opposite ends, said bolts pass through the top section and are threadedly engaged with lugs 20 securely embedded in a cross-beam C over 45 the doorway. The heads of the aforesaid bolts 19 are preferably of unusual size or configuration so as to require a special wrench or tool to turn them in order that an unauthorized individual will be prevented from gaining access to the 50 freight-car with an ordinary wrench or tool.

In order to assemble the sections, the lugs 10 of each section are inserted through the notches 8 in the guide-rails 6 and interlocked by the tongues 13 and apertured lugs 11 thereon where- 55

upon the sections are locked against removal by the top section when bolted to the cross beam C.

With this invention fully set forth it is manifest that a strong and thief-proof door is provided and, through the instrumentality of the flexible connections thereof to the freight-car, the sections cannot be removed or lost.

Having thus described my invention, what I claim and desire to protect by Letters Patent is:

10 The combination with a box type freight-car having doorways therein, guide-rails disposed on opposite sides of the doorway and having open notches in their free edges, a bottom door section, elongated lugs on the lower edge of the bottom section seated in apertures in the sill of the doorway, a plurality of sections resting on the lower way, a plurality of sections resting on the lower way, pairs of round lugs on the sides of the

sections adapted to pass through the notches in the guide-rails and slidably lodge behind the same, apertured lugs on the upper edges of certain of the sections, tongues on the lower edges of certain of the sections and adapted to seat in the apertured lugs, threaded lugs secured to a portion of the freight-car adjacent the top of the doorway in close proximity to the sides thereof of an elongated bracket secured to the top of the car inwardly of the door, a chain connected to one side of each section of the door with its opposite end connected to the bracket and, bolts, having special heads, passing through the uppermost section and threadedly engaging the threaded lugs.

15 WILLIAM JOSEPH LEWIS.
